UNITED STATES PATENT OFFICE.

ROGER WRIGHT, OF NEWCASTLE-UPON-TYNE, ENGLAND, ASSIGNOR TO W. G. ARMSTRONG, WHITWORTH AND COMPANY, LIMITED, OF ELSWICK WORKS, NEWCASTLE-UPON-TYNE, ENGLAND.

APPARATUS FOR CONTROLLING PUMPING-ENGINES.

SPECIFICATION forming part of Letters Patent No. 715,924, dated December 16, 1902.

Application filed April 4, 1902. Serial No. 101,409. (No model.)

To all whom it may concern:

Be it known that I, ROGER WRIGHT, engineer, a subject of the King of Great Britain, residing at Elswick Works, Newcastle-upon-Tyne, England, have invented certain new and useful Improvements in Apparatus for Controlling Pumping-Engines, of which the following is a specification.

In hydraulic governors for automatically regulating the speed of steam pumping-engines by the pressure in the delivery-pipe from the pumps it is usual to employ a spring-loaded plunger on the delivery-pipe to directly actuate the throttle-valve.

According to this invention the throttle-valve is worked by a pair of steam-pistons acted on by "live" steam from the boilers, the admission of the steam to either piston being effected by a small valve actuated by the spring-loaded plunger. It is also usual to provide a speed-governor driven from the crank-shaft to act in conjunction with the hydraulic governor.

According to this invention the speed-governor instead of having separate connections with the valve, as heretofore, acts through the same connections as the hydraulic governor.

The arrangement is as follows: A hydraulic cylinder in constant communication with the delivery-pipe has a spring-loaded plunger, to which a lever is pivoted. One arm of this lever is pivoted to a rod connected to the speed-governor, and the other arm is connected by a rod to the control-lever, which actuates the throttle-valve of the pumping-engine. If, therefore, either the speed of the engine or the pressure in the delivery-pipe varies, the governor-lever is turned about one or other of its pivots, and the valve is suitably moved.

The throttle-valve is preferably of the meter type, having at each end a piston working in a small cylinder. Live steam is admitted to one or other of these cylinders by a controlling-valve, whose rod has pivoted to it the controlling-lever, one arm of which is connected, as above mentioned, to the governor-lever, while the other arm is pivoted to the rod of the throttle-valve. If, therefore, the speed of the engine or the pressure in the de-

livery-pipe varies, so that the governor-lever is moved, the control-lever is moved also, at first turning about its pivot on the throttle-valve rod, so shifting the control-valve, and thereby admitting steam to one or other of the valve-cylinders, thus moving the throttle-valve. The throttle-valve rod during its movement carries the end of the control-lever with it, so that the control-valve becomes a "hunting-valve" and causes the throttle-valve to continue to open or close, as the case may be, until the speed and pressure become again normal.

By-pass pipes and a cock may be provided, so that sufficient steam can be allowed to pass the throttle-valve when closed to cause the engine to creep and not absolutely stop.

Figure 1 is a side elevation of the controlling mechanism, the crank-shaft being shown in section. Fig. 2 is a vertical section of the throttle-valve to a larger scale; and Fig. 3 is a section on the line 3 3, Fig. 2.

a is a hydraulic cylinder in constant communication with the delivery-pipe from the pump, and *b* is a plunger working in it.

c is a spring whose lower end bears upon the collar *b'*, fixed to the plunger *b*. The plunger is prolonged upward and has a lever *d* pivoted at *d'* to its upper end.

e is the crank-shaft of the engine, driving through the bevel-gear *e'* an ordinary speed-governor *f*, which operates a lever *g* in the usual manner. The lever *g* is pivoted at *g'*, and its other end is connected by rods *g²* *g³* and the bell-crank lever *g⁴* to the end *d²* of the lever *d*, whose other end *d³* is connected by the rod *h* to the end *j'* of the lever *j*. The lever *j* is also pivoted at *j²* *j³* to the rods *k* *l* of the control-valve *k* and the throttle-valve *l*, respectively. The valve *k* is hollow and works in a valve-chest *k²*, while the ends of the valve *l* work in cylinders *l²* *l³*. Steam is admitted to the chest *k²* from the steam-pipe *m* by the small pipe *k³*. The chest *k²* has in its ports leading to annular passages *k⁴* *k⁵* *k⁶*. The passage *k⁴* is connected by the pipe *n* to the cylinder *l³*, the passage *k⁵* to the exhaust, and the passage *k⁶* by the pipe *o* to the cylinder *l²*.

p is a by-pass pipe controlled by a cock *p'*, admitting sufficient steam to the engine to allow it to creep and not absolutely stop even when the throttle-valve is closed.

5. If the water-pressure in the delivery-pipe increases, the plunger *b* rises and turns the lever *d* about the pivot *d*², and, similarly, if the speed of the engine increases the governor *f* pulls the end *d*³ of the lever *d* downward, turning the lever about the pivot *d*'. In either case the rod *h* is pushed upward. The first result of this is to turn the lever *j* about the pivot *j*³ and pull the valve-rod *k'* upward, thereby admitting steam into the annular passage *k*⁶ and the cylinder *l*⁶, so forcing the throttle-valve downward and cutting off the steam. This movement of the throttle-valve lowers the pivot *j*³, so that when the rod *h* again descends, owing to the decrease 20 of the speed or water-pressure, steam is at once admitted to the cylinder *l*³ and the throttle-valve is opened.

What I claim is—

1. The combination of a throttle-valve, a cylinder, a piston in the cylinder operating the throttle-valve, a valve admitting steam to the cylinder, stems to the valves, a pressure-governor, and a lever connected to the two valve-stems and to the governor, the arrangement being such that the steam admitted to the cylinder by the movement of the admission - valve in one direction tends to move the throttle-valve in the opposite direction.
- 25 30 35 2. The combination of a throttle-valve, a cylinder, a piston in the cylinder operating the throttle-valve, a valve admitting steam to the cylinder, stems to the valves, a speed-

40 governor, and a lever connected to the two valve-stems and to the governor, the arrangement being such that the steam admitted to the cylinder by the movement of the admission-valve in one direction tends to move the throttle-valve in the opposite direction.

3. The combination of a throttle-valve, a cylinder, a piston in the cylinder operating the throttle-valve, a valve admitting steam to the cylinder, stems to the valves, a pressure-governor, a speed-governor, and a lever connected to the two valve-stems and to the 50 two governors.

4. The combination of a throttle-valve, a cylinder, a piston in the cylinder operating the throttle-valve, a valve admitting steam to the cylinder, stems to the valves, a pressure-governor, a speed-governor, a lever connected to the two valve-stems, and a second 55 lever connected to the two governors and to the first lever.

5. The combination of a throttle-valve, two 60 cylinders in which the ends of the throttle-valve work, a valve admitting steam to the two cylinders, stems fixed to the valves, a lever pivoted to the stems, a second lever, a connecting-rod pivoted to the two levers, a 65 hydraulic cylinder constantly open to the pressure in the delivery-pipe, a plunger in the cylinder pivoted to the second lever, a spring acting on the plunger, a speed-governor, and connections between it and the 70 second lever.

ROGER WRIGHT.
